[57] **CLAIM**

The ornamental design for an adjustable track light, as shown and described.

DESCRIPTION

FIG. 1 is a side elevational view of an adjustable track light showing our new design;

FIG. 2 is a front elevational view thereof;

FIG. 3 is a bottom plan view thereof;

FIG. 4 is a top plan view thereof;

FIG. 5 is a rear elevational view thereof;

FIG. 6 is an opposite side elevational view thereof;

FIG. 7 is a side elevational view of a second embodiment showing our new design;

FIG. 8 is a front elevational view thereof; and,

FIG. 9 is a bottom plan view thereof.

The second embodiment differs from the first only in the configuration of the reflector.
